UNITED STATES PATENT OFFICE.

JOHN C. FLYNN, OF ATLANTA, GEORGIA.

DESIGN FOR A BEDROOM-CABINET.

No. 38,437.

Specification for Design.

Patented Jan. 29, 1907.

Application filed December 28, 1906. Serial No. 349,927. Term of patent 7 years.

To all whom it may concern:

Be it known that I, JOHN C. FLYNN, a citizen of the United States, residing at Atlanta, in the county of Fulton and State of Georgia, have invented a new, original, and ornamental design for a Bedroom-Cabinet, of which the following is a specification, reference being had to the accompanying drawing, forming part thereof.

The figure is a perspective view of a bedroom-cabinet, showing my new design.

I claim—

The ornamental design for a bedroom-cabinet, as shown.

JOHN C. FLYNN.
